INDUCTION COIL

Hugh Boyd McGlade, Columbus, Ohio

Application December 20, 1947, Serial No. 793,019

2 Claims. (Cl. 321—8)

1

The invention relates to the elimination of induced current, generated at the time a normally open primary circuit of an induction coil is closed.

The induction coil (inductorium) is an apparatus that generates currents of induced electricity, and is generally used in the teaching of physiology and other allied sciences to induce response in living material, represented in both Figure 1 and Figure 2 by a resistance 5.

Figure 1 represents a conventional induction coil that will generate induced current at both the closing and the opening of a normally open primary switch 1.

Figure 2, an improved form of Figure 1, shows the invention in that it will automatically prevent the induced current from being generated when a normally open primary switch 1 is closed. When switch 1 is opened, induced current is generated in the usual manner.

In Figure 1, a normally open switch 1, in series with a battery 2 and a primary coil 3, when closed or opened, causes a momentary flow of induced current in a secondary coil 4 and a resistance 5. This current, hereafter referred to as "make" when switch 1 is closed and "break" when switch 1 is opened, is used in the following manner.

The hand operated switch 1 is closed and opened at regular intervals and the strength of the induced current is gradually increased following each opening of switch 1. The living material, represented by the resistance 5, is stimulated by the momentary flow of each effective induced current, and the resulting single response or contraction is in direct proportion to the strength of the current. Since the make current is always weaker than the following break current, the living material responds less to the make than to the following break, with but one exception: the maximum response of the living material is the same for either a maximum make current or a maximum break current. No difficulty is encountered in generating single induced break currents. Single induced make currents, however, are difficult to generate, as indicated by the following:

When switch 1, Figure 1, is closed, the switch contacts frequently rebound so that instead of closing only once, they close, open, and close again in rapid succession. Instead of inducing a single make, the resulting induced current flowing through the resistance 5 is a series of makes and breaks (3, 5 or more), immediately following each other. These makes and breaks summate

2

and, when effective, result in a response of the living material (resistance 5) that is greater than that caused by the break that follows when switch 1 is opened.

In order to eliminate the difficulty encountered at the closing of switch 1, Figure 1, the commercial induction coils, used in physiology laboratories, are equipped with a switch 6, wired in parallel with the secondary coil 4. To be effective, switch 6 must be closed before switch 1 is closed, and opened before switch 1 is opened. This procedure is entirely manual and the rapid closing and opening of the switches, in the proper sequence, is difficult, and not always positive; even when the control of switch 6 is made automatic with the manual control of switch 1. However, since induced current can be generated only while the strength of the direct current, in the primary coil 3, changes from zero to maximum (make), or from maximum to zero (break), the problem of automatically preventing induced current from being generated at the time switch 1 is closed, has been solved in the following manner:

The improved induction coil, represented by the schematic diagram in Figure 2, differs from the conventional (Figure 1) in that the secondary circuit is normally open instead of normally closed; and at the time switch 1 is closed, direct current flows not only through the primary coil 3, but also concurrently through a parallel relay coil 7, creating a magnetic field, in said relay coil 7, that closes a normally open relay switch 8, in series with a secondary coil 4 and the resistance 5.

The closing of switch 1 changes the strength of the direct current, in the primary coil 3, from zero to maximum in .002 of a second. During this time, and for an additional .001 of a second, the relay switch 8 remains open, due to inherent mechanical delay in closing. Since the relay switch 8 is open at the time switch 1 is closed, and remains open until after the current change takes place in the primary coil 3, it is impossible for a make current to be induced into the secondary coil 4 and flow through the resistance 5.

When the switch 1, Figure 2, contacts rebound upon closing, as previously described for Figure 1, the direct current, flowing concurrently through the primary coil 3 and the relay coil 7, is interrupted (changes from zero to maximum to zero) every .003 of a second; each interruption creating a magnetic field in the relay coil 7, lasting for .002 of a second. Since the duration of this magnetic field is .001 of a sec-

ond less than the time required to effect a closing of relay switch 8, relay switch 8 remains open until after the direct current interruptions cease, and a maximum current has been maintained in the relay coil 7, and the primary coil 3, for .001 of a second; thus preventing the induction of a series of makes and breaks in Figure 2, frequently generated in Figure 1, when switch 1 rebounds upon closing.

At the time switch 1, Figure 2, is opened, the relay switch 8 mechanically delays opening for .001 of a second. This inherent time delay factor is sufficient to permit the induced break current, picked up by the secondary coil 4, to flow uninterrupted through the resistance 5. The secondary circuit is broken as soon as the relay switch 8 opens, and the above cycle repeats automatically with the next closing and opening of switch 1.

I claim:

1. An induction coil comprising a primary coil, a primary switch, and a secondary coil, in combination with a direct current relay comprising a relay coil, and a normally open relay switch; said primary switch being connected in series with said primary coil, said relay coil being connected in parallel with said primary coil, and said relay switch being connected in series with said secondary coil; said relay switch subsequently closing on the closing of said primary

switch, and said relay switch subsequently opening on the opening of said primary switch, the secondary coil thus being open to prevent induction on the closing of said primary switch but closed to permit induction on the opening of said primary switch.

2. An induction coil comprising a primary coil, a primary switch, a secondary coil, and a normally open secondary switch; said primary switch being connected in series with said primary coil, and said secondary switch being connected in series with said secondary coil; said secondary switch subsequently and magnetically closing on the closing of said primary switch, and said secondary switch subsequently and magnetically opening on the opening of said primary switch; said secondary switch, open at the time said primary switch is closed, preventing induction, and said secondary switch, closed at the time said primary switch is opened, permitting induction.
